UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

ELECTRIC CIRCUIT BREAKER.

Application filed April 3, 1925. Serial No. 20,403.

My invention relates to an electric circuit controlling device and has particular reference to that type of control which has a plurality of breaks which are in series and 5 are closed in sequence and in which one of the breaks is arranged to open automatically when there is an excess current flowing in the circuit. The breaks are also arranged so that in closing the circuit the automatic 10 opening breaker is first closed by moving one of the other breakers to an open position so as to maintain the circuit open while the automatic break is being closed after which the circuit is closed by the other break 15 or breakers and preferably through manual operation. These breakers may also be termed switches.

Another object of my invention is to provide a mechanism in which the automatic 20 circuit breaker will automatically open whenever there is a movement in the other break or breakers having a tendency to open the circuit, and this arrangement will provide for a quick opening of the circuit prior 25 to the manual operated breaker opening the circuit.

Another object of my invention is to provide a device in which the mechanism will automatically open the circuit upon an 30 excess of current in the circuit.

Another object of my invention is to provide a mechanism in which it is impossible to close the circuit until the automatic breaker has been previously closed.

Another object of my invention is to provide a mechanism in which the circuit can be opened by hand at the will of an operator, but the circuit will be initially and automatically opened by an automatic breaker 35 prior to the circuit being opened by hand.

Another object of my invention is to prevent the opening of the circuit either through the automatic breaker or the hand breaker until the hand breaker has been 45 completely closed.

It is quite usual in connection with circuits carrying heavy currents to provide in the circuit a switch to automatically break the circuit in case of an overload, and also 50 a switch in series with the automatic switch and operated by hand to open and close the circuit and these switches are independent in operation. The intention of such an arrangement is that the operator in order to 55 close the circuit will first close the auto-

matic switch by hand and then close the manually operated switch, but this is not always followed and the result is that the operator may close the manually operated switch first and then attempt to close the automatic switch and if there is a short circuit or overload on the line and he attempts to hold the automatic switch closed as he can do, trouble is likely to result, or if he allows the automatic switch to open it may 60 result in injury to the operator.

Again, with the arrangement just described it is possible for an operator to open the circuit by first operating the manually operated switch, which is not constructed 70 as a rule to open circuits carrying a heavy current and the result may be very disastrous to the operator and the apparatus.

In my invention I have so combined the automatic and manually operated switches 75 that they will still operate in series, but it is impossible to completely close the circuit until the automatic switch has first been closed and is free to automatically open as soon as the manually operated switch is 80 moved to its closed position to complete the circuit, also it is impossible for the operator to open the circuit without first tripping the automatic switch to open the circuit and this action is followed by the opening of the 85 manually operated switch. These operations are brought about through the operation of a single handle moved in the proper directions.

I have shown the switching mechanism as 90 enclosed in a receptacle suitable for use in mines where the conditions are severe. Under such use the air is usually heavily charged with moisture which is very likely to condense, and, therefore, I install the 95 switching apparatus in a substantially enclosed receptacle formed of insulating material and provided with venting means such that the gases formed within the receptacle upon the opening of the automatic switch 100 may escape. At the same time, the venting is of such construction that the arc formed within the receptacle will be confined to the receptacle and thereby the ignition of external gases prevented.

My invention resides in the new and novel construction, combination and relation of the various parts hereinafter fully described and in connection with the drawings accompanying this specification in which:

- Fig. 1 is one face view of my invention in partial section and with the cover removed and shows the hand and automatic switches in closed relation with respect to the circuit.
- 5 Fig. 2 shows another face view of my invention, opposite to that shown in Fig. 1, in partial section with the cover removed.
- Fig. 3 is a sectional view of my invention shown on the zig-zag line 3—3 of Fig. 1.
- 10 Fig. 4 is a detail view of the automatic locking and tripping mechanism on the line 4—4 of Fig. 1, and is for the purpose of maintaining the automatic switch in closed position, but automatically releasing the same upon an excess current in the circuit or upon a movement of the operating handle at will of the operator in a direction to open the hand operated switch.
- Fig. 5 is a sectional view of the mechanism in Fig. 4, but shown on the line 5—5 of Fig. 1.
- 20 Fig. 6 is a detail of the same operating mechanism shown in Fig. 4, but taken on the line 6—6 of Fig. 1.
- 25 Fig. 7 is a detail view of a locking mechanism taken on the line 7—7 of Fig. 1 and is for the purpose of preventing the opening of the switch until the hand operated switch has been moved to its full closed position.
- 30 In the preferred embodiment of my invention I employ a casing 1 preferably of insulating material and formed to any shape desired to meet requirements. Formed within the casing is a transverse insulating
- 35 partition 2 and provided with an opening therein to receive the operating shaft 3 which projects through the side of the casing and acts as a core for the overload tripping coil 4. Mounted within the casing 1 and projecting therefrom is an arc chute 5 which has a cap 6 mounted thereon and secured to the chute 5 by means of the screws 7. Between the chute 5 and the cap 6 is an air space 8 communicating with the interior of the chute 5 so that any gases formed within the casing 1 will be allowed to escape from within the casing. It will be understood, of course, that the opposite faces of the casing 1 shown in Figs. 1 and 2 are provided with covers 9 and 10 and these covers are secured to the casing 1 by means of fastening devices 11 and 11a which are shown as through bolts and lugs with a nut 12 at one end, and these bolts 11 extend through the openings 13 in the casing 1 and the lugs 11a provide means to secure the device in position. The cover 10 is provided with a tight fitting opening to receive the shaft 3 and is provided with a bushing 14. Secured to the exterior end of the shaft 3 is an insulating handle 15 which I have shown as secured to the shaft 3 by threading although other well known means may be employed. By employing the member 3 as I do, it permits me to operate the mechanism
- 40 within the casing without any openings therein other than the opening 8.
- 45 Referring to Figs. 2 and 3, there is mounted upon the shaft 3 the energizing coil 4 which I have shown as wound with flat copper ribbon 16 having one end connected to the binding post 17 and the other end connected to the terminal 18 which is part of the stationary terminal for the manually operated switch.
- 50 Further referring to Figs. 2 and 3, there is mounted in the diaphragm 2 and adjacent to the coil 4 another coil 19 which is likewise wound with flat copper ribbon 20 and has one end connected to the terminal 21 and the other end connected to the terminal 22 which is the fixed terminal for the automatic opening switch. The terminals 17 and 21 are arranged for the connection thereto of the line circuit conductors 23 and 24. The terminals 17 and 21 comprise a metallic stud having the enlarged portion 25 with an opening therein to receive the terminal 26 of the cables 23 and 24 and preferably soldered thereto. The terminals 17 and 21 are provided with an exterior insulating receptacle 27 and the parts are held in position on the casing 1 by the nut and washer 28 and the terminals of the coils are held in position with respect to the terminals 29.
- 55 Referring further to the coil 19, I provide the same with a soft iron core 30 having one end positioned against the diaphragm 2 and the other end projecting beyond the coil 19 and provided with a soft iron plate 31 which also surrounds the shaft 3 with a reasonably tight fit thereby closing the magnetic circuit between the cores 3 and 30 on one side.
- 60 Mounted on the shaft 3 and secured in rotatable relation therewith is a switch blade 32 provided with a collar portion 33 in fixed engagement with the shaft 3. The blade 32 is adapted to engage between the fixed blades 34 and held by friction and when in engagement with the blades 34 the break in the circuit due to the manually operated blades 32 is closed.
- 65 Mounted upon the outer surface of the collar portion 33 of the blade 32, and rotatable relative thereto, is the automatically opening switch blade 35 composed preferably of a plurality of copper leaves secured to the carrier 36 which is provided with the collar portion 37 surrounding the collar portion 33. The switch blade 35 engages the terminal 32 which is secured to the insulating diaphragm 2 by means of the screws 38. The terminal 22 is provided with a stud 39 which projects through the diaphragm 2 and is connected to one end of the ribbon by means of the nut 40. Integrally secured to the outer surface of the collar 37 is a projecting lug 41 to which is secured

the spring 42 and which in turn is secured to a post 43 rigidly mounted in the diaphragm 2. The spring 42 is under tension and tends constantly to rotate the switch blade 35 about the axis of the shaft 3 in a direction to open the switch. The switch blade 32 has mounted upon its collar portion 33 an integral lug 44 and the collar portion 37 of the switch blade 35 has integrally secured thereto a lug 45 which is arranged to engage the lug 44 when the switch 35 is in an open position and held in engagement by means of the spring 42.

It will now be evident that if the switch blades 32 and 35 are in a closed position, as shown in Fig. 1, that there is a complete circuit from the cable 23 to the cable 24 through the terminal 17, the conductor 16 to the terminal member 18, through the switch blade 32 and through the switch blade 35 to the terminal 22 and from there through the conductor 20 of the coil 19 to the terminal 21 and thence to the cable 24. It will also be evident that if the switch blade 32 is closed with relation to the terminal 18 and the blade 35 is open that the lug 45 will engage the lug 44 and if the handle 15 is moved in the direction of the arrow A that the switch blade 35 will be rotated about the axis of the shaft 3 and into engagement with the terminal 22 and will be held in that position with proper holding mechanism later described and if the handle 15 is rerotated in the direction of the arrow B the blade 32 will engage with the terminal 18 and remain in that position as there is no force normally tending to move the blade in the direction of the arrow A and the circuit will be closed, as already pointed out, between the cables 23 and 24.

As already stated, I employ a mechanism for automatically locking the switch blade 35 in its closed position with the terminal 22 and this mechanism is also operable to release the blade 35 upon an excess current in the circuit controlled by the switch, or upon a movement of the handle 15 in the direction of the arrow A providing the switch 35 is in its closed position.

The automatic locking and tripping mechanism for the blade 35 comprises a base member 46 secured to the insulating diaphragm 2 by means of the screws 47. The base member 46 is provided with the spaced and overhanging arms 48 between which is pivoted, by means of the pin 49, a member 50, made of soft iron, and having one end positioned over the end of the operating shaft or core 3 and spaced therefrom. This member 50 may be termed an armature as it is caused to move about the pin 49 when the end thereof is attracted by the core 3 of the coil 4 when an excess of current is flowing therethrough.

Referring to Fig. 5, the armature is pro-

vided with an adjusting screw 51 which operates upon the spring 52 which in turn is secured to the base 46 and by means of the screw and spring the resistance to the movement of the armature 50 by the magnetism in the core 3 may be varied so that the current value in the circuit 23 at which the automatic switch 35 will open can be adjusted.

The screw 53 adjusts the relation of the armature with respect to the core 3. 75

To the base member 46 are also secured the spaced supports 54 to which is pivoted an arm 55 by means of the pin 56. The arm 55 overhangs the pin 56 at the pivoted end and interposed between the base 46 and the end of the arm 55 is a spring 57 tending to aid gravity in moving and maintaining the opposite end in a downward position, but permitting the same to move upward with a movement of the armature 50. The armature 50 and arm 55 are connected together by means of the adjustable connection 58 by means of which the relation between the arm 55 and armature 50 may be changed and which will cause the arm 55 to be moved upward about the pin 56 when the armature 50 is pivoted about its pin 49 either through an excess of current or through movement of the operating handle 15 in the direction of the arrow A, and this latter operation will be described shortly.

Projecting radially from the member 37 is an arm 59 provided with a roller 60 mounted upon the pin 61 and the roller is adapted to engage with the end of the arm 55 when the arm is in its lowered position and the engagement of the arm 59 with respect to the switch blade 35 and with the arm 55 is such that when the blade 35 is in its closed position the roller 60 will abut against the end face of the arm 55 and the arm 59 will be maintained in the position shown in Fig. 4 and the switch blade 35 in engagement with the contact 22. When the arm 55 is raised through the raising of the armature 50, as for instance, by an excess of current in the coil 4 then the arm 59 is free to move to the left, (see Fig. 4), and the switch blade 35 to move out of engagement with the contacts 22 through the tension of the spring 42. This will then bring the face of the lug 45 into engagement with the lug 44. 110

Referring to Fig. 6, I have shown mounted upon the switch blade 32 by means of screws 62 a forked member 63 between which is mounted a latch 64 to pivot about the pin 65 constantly urged by the spring 66 to move in the direction indicated by the arrow. The armature 50 is provided with a shoulder 67 which is adapted to be engaged by the latch 64 when the blade 32 is moved in a direction to open the switch or when the handle 15 is moved in the direction of the arrow A. When the latch 64 engages the 125 130

shoulder 67 and the movement of the blade 32 is continued the tendency for the latch will be to pivot about the pin 65 in the direction shown by the arrow, and this will 5 lengthen the vertical height between the pin and the point of the latch 64 and this will cause the arm 50 to be moved downward and the result will be the same as though the armature had been moved through excess 10 energization of the core 3, and the arm 55 will be raised and the switch blade 35 allowed to move to its open position under the influence of the spring 42. The relation of the latch 64 with respect to the ledge 15 15 67 is such that the blade 32 will not be out of engagement with the fixed contact blades 34 prior to the releasing of the switch blade 35. From this it will be seen that when the operator desires to open the circuit he has 20 only to move the handle 15 in the direction of the arrow A whereupon the latch 64 will so engage with the ledge 67 on the armature 50 as to cause the armature 50 to release the automatic switch blade 35, permitting 25 the switch blade 35 to open the circuit prior to the opening of the circuit by means of the blade 32 at the contacts 34.

From the description thus far, it will be seen that it will be impossible for an operator to completely close the circuit between the cables 23 and 24 without first closing the automatic switch blade 35 and then closing the manually operated switch 32, and it will also be observed that it is impossible 30 for the operator to open the circuit between the conductors 23 and 24 without first causing the automatic switch 35 to open and this switch is arranged to open the circuit in the most efficient manner, namely; by a 35 quick movement through a sudden release of the latching mechanism and the influence of the spring 42 and through a magnetic blow-out.

The magnetic blow-out comprises the plate 45 68, of soft iron, secured between the insulating member 69 and the side of the chute 5. This plate 68 is so bent, as shown in Fig. 3, that one end will rest upon the end of the core 3 so that the plate 68 will be magnetized 50 whenever current is flowing through the coil 4, and as this plate 68 rests opposite the core 30, lines of force will pass between the core 30 and the plate 68 and between the core 30 and the plate 68 the arc is broken when the switch blade 35 opens and the arc will be extinguished through the influence of the magnetic lines of force.

In order to compel the operator to move the switch blade 32 to its farthest closed position so as to insure the latch 64 engaging the armature 50, back of the ledge 67, I mount on the member 2 a plate 70 and this plate is provided with a plurality of teeth 71. Pivotal mounted on the arm 32 is a 60 latch 72 similar to the latch 64. This latch

is urged to the left by means of the spring 73 and when the switch 32 is so positioned that the latch 64 properly engages the armature 50 the latch 72 will have passed beyond the teeth 71 of the plate 70. When the operator moves the switch plate to an open position with the latch 72, as just described, it will pivot about its pin as the point of the latch 72 passes over the teeth 71. If, however, the switch blade 32 was not moved 75 far enough to its closed position the lower edge of the latch 72 will still be in engagement with the teeth 71 and when the operator then tends to open the switch blade 32 the engagement of the latch 72 with the teeth will prevent his doing so thereby making it necessary for him to move the operating handle 15 in the direction of the arrow B a sufficient amount so that the latch 64 will engage with the armature 50, after which 80 the operator then will be able to open the switch as desired.

The exposed end of the shaft 3, I protect by means of an enclosing cap of insulating material 74.

The operation of my invention is as follows:

In Fig. 1 I have shown the switch in a closed position and in order to open the switch it is only necessary for the operator to move the handle 15 in the direction of the arrow A and this in turn will cause the latch 64 to engage the armature 50 in such a manner as to depress the same thereby raising the arm 55 and releasing the automatic switch blade 35, whereupon the spring 42 will cause the blade 35 to move out of engagement with the contact 32 at a high rate of speed and the magnetism in the coils 4 and 19 will produce an extinguishing effect upon the arc thereby opening the circuit quickly and efficiently. As soon as the automatic switch 35 is open further movement of the handle 15 in the direction A is unnecessary.

In order to close the circuit, however, it is necessary to move the switch handle 15 in the direction of the arrow A and the engagement of the lug 44 with the lug 45 will cause the switch blade 35 to move into engagement with the contact 22 and when the blade has moved sufficiently far the roller 60 will have passed beyond the end of the arm 55, allowing the arm to drop and engage with the roller 60 thereby maintaining the blade 35 in engagement with the contact 22 and placing the spring 42 under tension. In order to complete the closing of the circuit, it is then necessary for the operator to move the switch handle 15 in the direction of the arrow B and this will bring the blade 32 into engagement with the contacts 34 thereby completing the closing of the switch and the closing of the circuit 23-24. With the movement of the handle 15 in the direction 110

of the arrow B the latch 64 will engage with the armature 50, as already explained, resetting the mechanism for operation.

With the switch closed, as shown in Fig. 1, and with an excess of current flowing through the switch, the coil 4 will be energized beyond a predetermined amount and this will cause the armature 50 to be attracted thereby releasing the automatic switch through the raising of the arm 55 and the circuit will be automatically opened after which it may be closed, as already explained, but making it necessary to first close the automatic switch blade 35 so that there should be any short circuit or overload upon the line, the switch blade 35 is free to open automatically immediately upon the closing of the switch blade 32. In closing the switch, if the operator has not moved the handle a sufficient distance in the direction of the arrow B then he will be unable to open the switch as the latch 72 will engage with the teeth 71 and this will cause him to then move the handle 15 a sufficient distance in the direction of the arrow B so that the latch 64 will properly engage with the armature 50 thereby insuring the automatic opening of the switch blade 35 prior to the opening of the switch blade 32.

I have shown one form of construction embodying my invention, but it will be evident that many changes and modifications may be made therein which will fall within the scope of my invention. Therefore, I do not limit the annexed claims to the specific device illustrated and described, but desire to cover all modifications and substitutions which come within the scope and spirit of my invention.

40 I claim:

1. A circuit controlling device comprising in combination, a circuit breaker and a switch connected in series in a circuit, a trip mechanism to automatically hold the circuit breaker in its closed position, an electromagnet to operate the trip mechanism and having a core acting as the axis for the switch and circuit breaker, means on the switch to engage the trip mechanism when the switch is closed and to trip the mechanism and release the circuit breaker when the switch is moved to its open position, but before the switch has opened.

2. A circuit controlling device comprising in combination, a rotatable core of magnetic material, means to operate the core about its axis, a switch blade mounted on the core to rotate therewith, a circuit breaker mounted upon the core and arranged to rotate relative thereto about the axis of the core, means to move the circuit breaker to an open position, means to close the circuit breaker when the core is rotated in one direction, a coil surrounding the core to energize the core and connected in series with

the circuit breaker, a trip mechanism to hold the circuit breaker in a closed position and means on the mechanism operated by the energized core to trip the mechanism and release the circuit breaker when the circuit in the coil exceeds a predetermined amount.

3. A circuit controlling device comprising in combination, a rotatable core of magnetic material, a coil surrounding the core to energize the core, means to rotate the core, a switch mounted on the core to rotate therewith to an open or a closed position, a circuit breaker mounted on the core to rotate relative thereto about its axis and in series with the switch to open or close a circuit, means tending to open the circuit breaker, trip mechanism to hold the circuit breaker closed and arranged to trip and release the circuit breaker when the core is energized beyond a predetermined amount and arranged to coact with the switch to be tripped by the opening movement of the switch.

4. A circuit controlling device comprising a receptacle divided into two compartments by a transverse partition integrally formed with the sides of the receptacle, a removable cover for each compartment, a transversely disposed and rotatable core passing through the partition and one cover, a circuit breaker mounted on the core within one compartment and to rotate relative to the core, means to rotate the core, an energizing coil mounted on the core and within the other compartment, a trip mechanism to hold the circuit breaker closed, means tending to open the circuit breaker, means on the core and operated thereby to close the circuit breaker or to open the circuit breaker by operating the trip mechanism when the core is rotated in one direction or the other.

5. A circuit controlling device comprising in combination, a circuit breaker, a trip mechanism to hold the circuit breaker closed, means tending to open the breaker, a rotatable and energizable core to trip said mechanism and release the circuit breaker whenever the core is rotated in one direction or over energized and a coil to energize the core.

6. A circuit controlling device comprising in combination, a circuit breaker and a switch in series and controlling a circuit and rotatable about a common axis, a rotatable and energizable core having an axis common with the aforesaid axis and operating when rotated to open or close the said switch and circuit breaker depending upon the direction of rotation, a coil to energize the core and trip mechanism to hold the circuit breaker closed and operated by either the over energization or rotation of the core to release the circuit breaker.

7. A trip mechanism for holding a circuit breaker in one of its positions, an electric magnet having its coil energized from

a source of power, a frame, a lever pivoted at one end and having a roller at the other end to engage in thrust relation the circuit breaker, an armature pivoted at one end and having its other end adjacent the electromagnet to be influenced thereby when the magnet is over energized, a spring and adjustment therefor to regulate the amount of resistance of the armature to the influence of the magnet, means to regulate the normal relation of the armature to the magnet, and adjustable means connecting the armature and the aforesaid lever to move the lever out of the path of the circuit breaker when the current in the coil exceeds a predetermined amount.

8. A trip mechanism as characterized in claim 7 and having in addition manually operated means to impart to the armature an action equivalent to that given it by the over energized magnet to trip the circuit breaker at will of the operator.

9. A circuit controller comprising a switch blade to make and break a circuit, a circuit breaker to connect the circuit thereto and automatically disconnect it, a handle to manually operate the switch, means to control the opening of the circuit breaker and to interlock with the switch blade and means to prevent the manual opening of the switch blade after once closing the circuit until the switch blade has moved a predetermined amount in closing.

10. A trip mechanism for holding a circuit breaker in one of its positions, an electric magnet having its coil energized from a source of power, a frame, a lever pivoted at one end and having a roller at the other end to engage in thrust relation the circuit breaker, an armature pivoted at one end and having its other end adjacent the electromagnet to be influenced thereby when the magnet is over energized, a spring and adjustment therefor to regulate the amount of resistance of the armature to the influence of the magnet, means to regulate the normal relation of the armature to the magnet, adjustable means connecting the armature and the aforesaid lever to move the lever out of the path of the circuit breaker when the current in the coil exceeds a predetermined amount, a manually operated switch to engage and close the circuit breaker and to close the circuit, means on the switch to operate the armature when the switch is operated manually to its open position after being closed to trip the armature and release the circuit breaker.

11. In a switch device the combination of a support, a rotatable shaft mounted thereon, an operating handle secured to the shaft, a switch blade pivotally mounted on the shaft and adapted to engage a contact, holding means to automatically engage the blade to maintain it in engagement with the contact, means tending to move the blade out

of engagement with the contact, means secured to the shaft to rotate therewith and having means to engage the blade when the handle is rotated in one direction and other means to engage the holding means when the handle is rotated a predetermined distance in the other direction to trip the holding means and release the blade, the blade remaining closed when the handle is in an intermediate position.

12. A circuit controlling device comprising in combination an automatic circuit breaker and a switch connected in series to control a circuit, holding means operated by the opening movement of the switch to trip the circuit breaker, and means to prevent an opening movement of the switch after it has been partially closed until the switch has been fully closed and in position to engage and trip the holding means upon an opening movement of the switch.

13. A circuit controlling device comprising in combination an automatically opening circuit breaker, means to hold the circuit breaker in its closed position, a hand operated switch in series with the circuit breaker and having two positions and adapted to close the circuit breaker when moved in the direction of its open position and close the circuit when moved in the other direction, pivotally mounted means adapted to engage the said holding means after the switch has been moved to its fully closed position and to trip the holding means when the switch is later moved to its open position and means to prevent opening the switch after having once closed to any degree before the pivotally mounted means is in position to energize the holding means.

14. A circuit controlling device comprising in combination a circuit breaker and a switch connected in series, a trip mechanism to automatically engage and hold the circuit breaker in its closed position, means to engage and release the circuit breaker when the switch is moved toward its open position, means to blow out the arc formed at the circuit breaker contacts when opened, a receptacle of insulating material to confine the said flash and prevent its contact with surrounding gases, an opening in the receptacle and an inverted cup shaped insulating member over said opening and forming a passage with the receptacle to prevent pressure within the receptacle and allow the escape of gases formed by the flash.

15. A circuit controlling device comprising in combination a circuit breaker, means to move the circuit breaker to its open position, trip mechanism to hold the circuit breaker in a closed position, manually operated means to trip the circuit breaker at will and comprising a pivotally mounted member, a handle thereon, a latch to engage the trip mechanism and mounted on the piv-

totally mounted member and an automatic operating pawl and ratchet mechanism to prevent movement of the manually operated means in one direction until moved a predetermined amount in the other direction.

16. A circuit controlling device comprising in combination an enclosing casing, a circuit breaker and a switch connected in series to control a circuit and mounted within the casing, a trip mechanism to hold the circuit breaker in a closed position and means to open the circuit breaker when released, a rotatable core extending through one side of the case and projecting therefrom and a coil connected to a source of power to energize the core, the core being arranged to trip the trip mechanism and release the circuit breaker when the coil is overenergized and to open and close the circuit breaker when rotated and a handle secured to the rotatable core outside the casing to operate the circuit breaker.

17. A circuit control device comprising in combination, a circuit breaker, a trip mechanism to hold the circuit breaker in a closed position until tripped by an electromagnet when the current in its operating coil exceeds a predetermined amount, a switch in series with the circuit breaker and held closed by friction and adapted to remain closed when the circuit breaker is opened by an overload but capable of operating the tripping mechanism when moved manually to an open position, a magnetic blow-out coil and core acting upon the flash at opening the circuit breaker to extinguish the same and pivotal means on the switch to engage stationary means to compel the switch to be moved a predetermined amount in the closed direction before it can be moved to its open position after once closing.

In testimony whereof I affix my signature.

HOMER P. CHANDLER.
